UNITED STATES PATENT OFFICE

STACY B. HASELTINE, OF CHICAGO, ILLINOIS, ASSIGNOR TO W. H. MINER, INC., OF CHICAGO, ILLINOIS, A CORPORATION OF DELAWARE

CAR CONSTRUCTION

Application filed December 5, 1929. Serial No. 411,733.

This invention relates to improvements in car construction and especially to means for connecting the body and truck bolsters of railway cars.

One object of the invention is to provide a combined locking and center pin for connecting the bolsters of a railway car, which is of simple, rugged design, and may be readily applied to and detached from the bolsters, wherein the pin includes a shank portion having means at opposite ends having shouldered engagement with shoulders adjacent the center pin openings of the respective bolsters, said means at one end of the pin at least being detachable to allow removal of the pin or separation of the bolsters, the detachable means including a member displaceable with respect to the pin to interlock the same therewith.

A further object of the invention is to provide a pin of the character indicated in the preceding paragraph, wherein the detachable member is rotatable with respect to the pin to interlock the same therewith, the pin being so formed at one end portion thereof as to pass through an opening provided in the rotatable locking member when the latter is in one position and having shouldered engagement with said member when the latter is displaced by partial rotation of the same, and wherein keeper means is provided for locking the pin and said rotatable member against relative rotation when in shouldered engagement.

A still further object of the invention is to provide in connection with a center pin of the character described adjustment to compensate for wear of the parts and also lock the pin against rotation with respect to one of the bolsters.

Other objects of the invention will more clearly appear from the description and claims hereinafter following.

In the drawing, forming a part of this specification, Figure 1 is a top plan view,

broken away, of a portion of the body bolster of a railway car illustrating my improvements in connection therewith. Figure 2 is a vertical, sectional view, corresponding substantially to the line 2—2 of Figure 1 through the cooperating body and truck bolsters of a car. Figure 3 is a vertical, sectional view, corresponding substantially to the line 3—3 of Figure 2, and Figure 4 is a horizontal sectional view corresponding substantially to the line 4—4 of Figure 3.

In said drawings, 10 designates the body bolster of the railway car and 11 the cooperating truck bolster. The body bolster is provided with the usual downwardly projecting bearing portion 12, which is in the general form of a spherical member. The truck bolster is provided with a cooperating bearing block 13 disposed within a pocket 14 at the top of the truck bolster and having a concave bearing seat 15 at the top thereof within which the bearing member 12 of the body bolster engages.

In carrying out my invention, I provide the body and truck bolsters with aligned center pin receiving openings 16 and 17, the body bolster being provided with a pocket 18 at the upper end of the opening 16 of larger cross sectional area than said opening. The truck bolster is provided with an annular shoulder 19 at the lower end of the pin receiving opening 17 thereof. The top and bottom portions of the truck bolster are connected by the usual spaced webs, as clearly shown in Figure 2, which define a pocket 20 therebetween. The bearing block 13 is provided with an opening 21 corresponding in size to the opening 17 of the truck bolster. The openings 17 and 21 are preferably of circular cross section. The bottom portion 80 of the opening 16 of the body bolster is also preferably of circular cross section and immediately above said portion opposed wall sections of said opening converge inwardly 85 as shown in Figure 2, the extreme upper end 90

portion of said opening being of oblong cross section as clearly indicated in Figure 4.

My improved center pin proper comprises broadly a center pin member A, a retaining element B composed of a plurality of sections; and a U-shaped locking element C.

At the bottom end, the shank portion of the pin member is of substantially cylindrical form so as to fit the corresponding circular openings 17 and 21 of the truck bolster and the bearing block 13 and also fit the circular portion at the bottom of the opening 16 of the body bolster. At the bottom end, the pin is provided with an integral head member 22 adapted to have shouldered engagement with the annular shoulder 19. Above the cylindrical shank portion, the pin member A has the opposite side sections thereof tapered inwardly, as most clearly shown in Figures 2 and 3, thereby providing an oblong upper end section on the shank. At the upper end, the pin member is provided with a partial head 23 formed by laterally projecting lugs or flanges on diametrically opposite sides of the shank. The partial head section 23 is of such a size as to pass through the center pin receiving openings of the bolsters when the pin is being assembled with the same, and also pass through the portion of oblong cross section 30 of the opening 16 when said pin is properly positioned. The pin is of such a length that when assembled with the bolsters the partial head member 23 at the upper end thereof is spaced an appreciable distance above the bottom of the pocket 18. The bottom wall of the pocket adjacent the opening 16 forms a retaining shoulder 24 which prevents removal of the pin in a manner hereinafter pointed out.

The retaining element B comprises a plurality of ring-like washers or shims 25-25, which are interposed between the shoulder 24 of the body bolster and the partial head 23 of the pin A. The number of shims or washers employed may be varied so as to space the head 22 at the bottom end of the pin the desired distance from the shoulder 19 of the truck bolster to provide the required clearance between these parts. The retaining element B, in the present instance, is shown as composed of four similar ring-like members 25. Each member 25 has an oblong central opening 26 of such a size as to permit free passage therethrough of the partial head 23 of the pin A when the rings 25 are in such a position that the openings thereof register with the projecting lug-like sections forming the partial head 23. When the parts of the pin are assembled so as to lock the bolsters together, the retaining element B is so disposed that the oblong opening thereof is out of alignment with the projecting lugs of the partial head 23 so that said head will have shouldered engagement with the retaining element B to prevent removal of the pin.

In order to prevent accidental relative rotation of the retaining element B and the pin A after the parts have been assembled and the locking element has been partially rotated with respect to the pin, the U-shaped locking element C is employed. As most clearly shown in Figures 2 and 3, the U-shaped locking element has a pair of downwardly extending parallel arm portions 36-36, which are enlarged at their bottom ends and are adapted to fit within the outer portions at opposite ends of the elongated opening of the retaining element B. As most clearly illustrated in Figures 2, 3 and 4, the opposite sides of the upper end portion of the pin A are flattened as indicated at 27-27 and the inner sides of the arms 36-36 of the U-shaped member C bear on said flattened portions. The upper end portion of the opening 16 of the body bolster, which is contracted as shown, corresponds in horizontal section to the horizontal cross section of the corresponding shank portion of the pin A, as most clearly shown in Figure 4.

As will be obvious, due to the interfitting relation of the upper end of the shank portion and the contracted portion of the opening 16, relative rotation of the pin with respect to the body bolster 10 is prevented. The upper connecting section of the locking member C is preferably spaced from the upper end of the pin A, as shown in Figures 2 and 3, so as to permit vertical adjustment of the pin with respect to said member. When the parts become worn, so that the amount of clearance between the fixed head 22 and the shoulder 19 of the truck bolster is increased, this wear may be compensated for by adding a shim or washer 25 to the retaining element B, which will effect lifting of the partial head 23 of the pin, which head is supported on the retaining element. As will be obvious, by thus adjusting the parts, the amount of clearance between the upper end of the pin and the connecting portion of the U-shaped locking member C is decreased.

In the present instance, the locking center pin is shown as supported by a shelf 28 in the form of a flanged plate having the vertical flanges thereof riveted to the connecting webs of the truck bolster. The shelf 28 directly supports the head 22 of the locking center pin A. As will be evident, the locking center pin is fully operative without the supporting shelf 28, but this shelf forms a convenient supporting means for the pin when the pin is unlocked from the body bolster and it is not desired to completely remove the pin but merely lift the body bolster from the truck bolster.

In applying the center pin to the body and truck bolsters of the car, the pin is inserted from the bottom of the truck bolster through the aligned openings of the truck and body

bolsters, the pin being so disposed that the oblong partial head member 23 at the upper end thereof registers with the oblong section of the upper end of the opening of the truck bolster. When the pin has been completely inserted with the partial head portion 23 thereof, spaced above the retaining shoulder 24 of the body bolster, the locking element B is applied by registering the oblong openings of the sections 25 thereof with the partial head and dropping the same over said head. After the sections 25 are in position below the partial head 23, the same are bodily rotated about the pin through an angle of 15 90° so as to bring the oblong opening of the retaining element out of alignment with the projecting portions of the partial head member 23 and place the opposite ends of 20 the opening of the retaining element B in alignment with the flattened sides of the pin A. The U-shaped locking element C is then applied by inserting the arms 36—36 thereof within the end portions of the opening of the retaining element B, thereby locking the 25 retaining element B against rotation with respect to the pin. After the pin A has been assembled to the truck bolster, the supporting shelf 28 may be applied and secured to the truck bolster by riveting the same. 30 When it is desired to separate the bolsters of the car without actually removing the pin from the truck bolster, the locking element C is first removed so as to permit rotation of the sectional retaining element B. The element B is then turned to a position where the oblong opening thereof registers with the projecting portions of the partial head 23, whereupon the retaining element B may be lifted out of engagement with the pin A. 35 As will be evident, the body bolster may then be lifted from the truck bolster. In case it is desired to remove the pin entirely, the shelf 28 is detached and the pin dropped through the truck bolster.

40 I have herein shown and described what I now consider the preferred manner of carrying out my invention, but the same is merely illustrative and I contemplate all changes and modifications that come within the scope of the claims appended hereto.

I claim:

1. In car construction, the combination with cooperating body and truck bolsters having alined center pin receiving openings and retaining shoulders adjacent said openings; of a connecting member for said bolsters extending through said alined openings and having retaining means at one end in engagement with the shoulder of the corresponding bolster to retain said connecting member against movement in one direction; and a retaining element cooperating with the other end of the connecting member, said element being provided with an opening and 50 said connecting member having the last

named end so formed as to pass through said opening, when the retaining element is in one position, and have shouldered engagement with the retaining element when the same is displaced, said retaining element engaging the shoulder of the cooperating bolster to retain said connecting member against removal in the other direction. 70

2. In car construction, the combination with cooperating body and truck bolsters having alined center pin receiving openings; of a center pin extending through said openings, said pin having shouldered engagement at one end with the shoulder of one of said bolsters to prevent removal of the pin in one direction; means at the other end of the pin having shouldered engagement with both the pin and the other bolster to prevent removal in a reverse direction, said pin having an enlargement at said last named end providing the shouldered engagement between the same and the retaining element, said retaining element having an opening through which said enlargement is adapted to pass when said element is in one position and through which said enlargement is prevented from passing when said element is turned through a partial rotation to bring said enlargement into shouldered engagement. 85

3. In car construction, the combination with body and truck bolsters having alined center pin receiving openings and retaining shoulders adjacent said openings respectively; of a center pin extending through said openings and having means at one end thereof having engagement with the shoulder of one of said bolsters; and detachable retaining means at the other end of the pin having shouldered engagement with the other bolster, the shank portion of said pin extending through the last named bolster and the corresponding pin receiving opening being so formed as to prevent relative rotation of said pin and said bolster. 95

4. In car construction, the combination with body and truck bolsters having alined center pin receiving openings and retaining shoulders adjacent said openings respectively; of a connecting center pin extending through said openings, said pin having a head member at one end having shouldered engagement with the corresponding retaining shoulder, the pin at the other end being provided with lateral projections; and a retaining element having shouldered engagement with the shoulder of the corresponding bolster, said retaining element having an opening through which the corresponding end of the pin is adapted to pass when said element is in one position and with which when said element is given a partial rotation, said projections are adapted to have shouldered engagement to retain said pin. 110

5. In car construction, the combination with cooperating body and truck bolsters 130

having alined center pin receiving openings; of a connecting center pin extending through said openings and having shouldered engagement with one of said bolsters adjacent the outer end of the corresponding opening, the other end of the pin having the shank portion thereof reduced in cross section and being provided with a partial head member at said end, said partial head member being of 10 such a size as to pass through the center pin receiving openings; and a retaining element having shouldered engagement with the other bolster, said retaining element having an opening therethrough of such a contour 15 as to permit passage of the partial head when said element is in one position, and when given a partial rotation to prevent passage therethrough of said partial head to hold said pin to said bolsters.

6. In car construction, the combination with body and truck bolsters having alined center pin receiving openings and retaining shoulders adjacent said openings respectively; of a connecting center pin extending 20 through said openings and having a head at one end having engagement with the retaining shoulder of one of said bolsters, a portion of said shank extending through the other bolster and being of reduced cross section, 25 and the cross sectional outline of said shank portion and the shape of the corresponding portion of the pin opening of the bolster being such as to prevent relative rotation of the pin and corresponding bolster, said end 30 of the pin outwardly of the reduced portion being enlarged and of oblong cross section; and a retaining element having shouldered engagement with said last named bolster, said element having an oblong opening 35 through which said oblong enlarged section of the pin is adapted to pass when alined therewith, said element when rotated to bring said opening out of alinement with said enlarged section of the pin providing shouldered engagement with said enlargement to 40 retain said pin.

7. In car construction, the combination with cooperating body and truck bolsters of a railway car having alined center pin receiving openings; of a center pin extending through said openings, said pin having shouldered engagement at one end with the shoulder of one of said bolsters to prevent removal of the pin in one direction; means at 50 the other end of the pin having shouldered engagement with both the pin and the other bolster to prevent removal in a reverse direction, said pin having an enlargement at said last named end providing the shouldered engagement with the retaining element, said retaining element having an opening through which said enlargement is adapted to pass when said element is in one position and through which said enlargement is 55 prevented from passing when said element

is turned through a partial rotation; and means for locking said retaining element and pin against relative rotation.

8. In car construction, the combination with body and truck bolsters having alined center pin receiving openings and retaining shoulders adjacent said openings respectively of a connecting center pin extending through said openings, said pin having a head member at one end having engagement with the corresponding retaining shoulder, the pin at the other end being provided with lateral projections; a retaining element having shouldered engagement with the shoulder of the corresponding bolster, said retaining element having an opening through which the corresponding end of the pin is adapted to pass when said element is in one position and which when given a partial rotation is engaged by said projections to retain said pin; and a U-shaped locking element embracing said pin and having the arms thereof extending into the opening of said retaining element to lock said element and pin against relative rotation. 90

9. In car construction, the combination with body and truck bolsters having alined center pin receiving openings and retaining shoulders adjacent said openings respectively; of a connecting center pin extending through said openings, said pin having a head member at one end having shouldered engagement with the corresponding retaining shoulder, the pin at the other end being provided with lateral projections; and a retaining element 95 having shouldered engagement with the shoulder of the corresponding bolster, said retaining element having an opening through which the corresponding end of the pin is adapted to pass when said element is in one position and with which, when said element is given a partial rotation, said projections are adapted to have shouldered engagement to retain said pin, said retaining element being adjustable in height to compensate for 100 wear of the parts and maintain the proper spacing between the head member and shoulder of the corresponding bolster. 105

10. In car construction, the combination with body and truck bolsters having alined center pin receiving openings and retaining shoulders adjacent said openings respectively; of a connecting center pin extending through said openings and having a head at one end having shouldered engagement with the retaining shoulder of one of said bolsters, a portion of the shank of said pin extending through the other bolster being of reduced cross section and the cross sectional outline of said shank portion and the shape of the 115 corresponding opening of the bolster being such as to prevent relative rotation of the pin and corresponding bolster, said end of the pin outwardly of the reduced portion being enlarged and of oblong cross section; and 120
